UNITED STATES PATENT OFFICE.

HENRY KERSHAW, OF KEARNEY, NEW JERSEY.

COMBINED PUNCH AND SPACING DEVICE.

1,306,013.

Specification of Letters Patent. Patented June 10, 1919.

Application filed September 3, 1918. Serial No. 252,392.

To all whom it may concern:

Be it known that I, HENRY KERSHAW, a subject of the King of Great Britain, residing at Kearney, in the county of Hudson 5 and State of New Jersey, have invented certain new and useful Improvements in Combined Punches and Spacing Devices, of which the following is a specification.

My invention relates to a combined punching and spacing device.

An important object of the invention is to provide means whereby a punch may be quickly and conveniently employed for forming starting drill openings, which are 15 equidistantly spaced, without the employment of dividers, ordinarily used for spacing such openings.

A further object of the invention is to provide a device of the above mentioned 20 character, which is adjustable to compensate for wear upon the punch element, or ring element, or both.

Other objects and advantages of the invention will be apparent during the course 25 of the following description.

In the accompanying drawings forming a part of this specification and in which like numerals are employed to designate like parts throughout the same,

30 Figure 1 is a side elevation of a device embodying my invention,

Fig. 2 is a central longitudinal sectional view through the same, parts being in elevation,

35 Fig. 3 is a side elevation of the punch element removed,

Fig. 4 is a central longitudinal sectional view through the tubular ring punching element, the same being removed,

40 Fig. 5 is a horizontal sectional view taken on line 5—5 of Fig. 2,

Fig. 6 is a similar view taken on line 6—6 of Fig. 2, and,

45 Fig. 7 is a plan view of a section of metal, illustrating the use of the device.

In the drawings, wherein for the purpose of illustration is shown a preferred embodiment of my invention, the numeral 5 designates a punch element, having its forward 50 end pointed, as shown at 6. Near its rear end the element 5 has an enlarged portion 7, which is screw-threaded, as shown at 8. This enlarged portion or shank is equipped with a preferably milled head 9, 55 to turn the punch element.

The numeral 10 designates a tubular ring punching element, as a whole, which is mounted to slide upon the punch element 5. This ring punching element has its forward end sharpened, as shown at 11. The element 10 carries a radial screw 12, projecting into a longitudinal groove 13, formed in the punch element 5. This screw and groove retains the punch element and tubular ring punching element assembled, but 60 does not prevent the reciprocation of the element 10, upon the punch element 5.

The numeral 14 designates an adjustable stop, as a whole, comprising a ring 15, having screw-threaded engagement with the enlarged portion 7. This ring carries a sleeve 16. The lower end of the head 9 projects into the sleeve 16, and the lower end of this sleeve receives a reduced extension 17, of the element 10. This reduced extension is 75 adapted to contact with the ring 15, thus serving as a stop.

A compressible coil spring 18, surrounds a portion of the punch element 5, and is confined between the enlarged portion 7 and 80 a shoulder 18' of the element 10, and thus serves to force the element 10 forwardly upon the punch element 5.

In Fig. 7, the numeral 19 designates a section of sheet metal, such as iron or steel. 85 This section of metal has marked thereon a triangle 20, to be cut therefrom.

In the use of my device, the punch element 5 is placed near a portion of the line 20, so that the circular edge 11 will contact 90 with the same. The head 9 is now struck with a hammer, whereby the punch element 5 forms the opening 21, for the drill, and the edge 11 forms the ring 22. The device is then moved to the right so that the edge 95 11 will contact with the line 20 and the ring 22, subsequent to which the head 9 is struck with the hammer, providing the next opening 21, and ring 22. It is obvious that the series of openings 21 may thus be 100 readily formed, and these openings will be equidistantly spaced. The openings 21 are now employed to start a drill, and when the drill openings are cut, the inner portion of the metal may be knocked out, as 105 is well known, the drill having the same diameter as the ring punching element.

When the punch element 5 is shortened by grinding of the point 6, the stop element 14 is turned upon the enlarged portion 7, 110

to be adjusted longitudinally thereof, so that the element 10 may move rearwardly a greater distance upon the element 5.

It is obvious that by removing the screw 5 12, the punch element 5 may be withdrawn from the element 10, and the stop element 14 removed from the punch element 5.

It is to be understood that the form of my invention herewith shown and described 10 is to be taken as a preferred example of the same, and that various changes in the shape, size, and arrangement of parts may be resorted to without departing from the spirit of the invention or the scope of the subjoined claims:

Having thus described my invention, I claim:—

1. A combined punching and spacing device, comprising a punching element, a tubular ring punching element mounted to slide upon the punching element, and a stop carried by the punching element to contact with one end of the tubular ring punching element.
- 25 2. A combined punching and spacing device, comprising a punching element, a tubu-

lar ring punching element mounted to slide upon the punching element, yielding means to oppose the longitudinal movement of the tubular ring punching element in one direction with relation to the punching element, and a stop carried by the punching element to contact with one end of the tubular ring punching element.

3. A combined punching and spacing device, comprising a punching element, a tubular ring punching element mounted to slide thereon, yielding means to oppose the longitudinal movement of the tubular ring punching element in one direction with relation 30 to the punching element, and a stop longitudinally adjustably mounted upon the punching element and arranged to contact with one end of the tubular ring punching element.

In testimony whereof I affix my signature in presence of two witnesses.

HENRY KERSHAW.

Witnesses:

ALICE MYLES,
GABRIEL B. REID.
